BASEMENT WINDOW CONSTRUCTION

Lyle Carnick, Detroit, Mich., assignor to Copco Steel & Engineering Company, Detroit, Mich., a corporation of Michigan

Application January 7, 1954, Serial No. 402,692

3 Claims. (Cl. 189—69)

This invention relates to a basement window construction and more particularly to a basement window having a removable ventilator installed in a frame, the ventilator having means to balance to control of the ventilator in opening, closing and locking the same in the frame, the control means also embodying the locking mechanism.

The instant invention employs metal frames and ventilators, but the construction is also applicable to wooden units. Most basement window units are arranged with center mounted locking levers or devices. When these levers are grasped to open or close the ventilators, the control is very uncertain, precarious and often ineffective, because the ventilator can swing to either side of center thus going easily out of control in opening or closing operations. Ventilators of metal are often quite heavy in weight, being fitted with glass panes and sealing putty. Also, excessive loading of the frame top bar causes difficulty in operating such center lever locking devices, which often become jammed or distorted. A further difficulty in control is the fact that basement windows are located near the basement ceiling or joist line, above the heads of most persons. Very often ventilators are dropped out of frames or improperly locked or jammed in their frames because the locking lever is located in the middle of the ventilator.

Side arm connected window ventilators are also difficult to control in that the disengaging arm slots must be very carefully positioned at both sides of the ventilator before the latter can be freed of the arms. This often is difficult because a view of the arm slot positions is not always possible, and then the operation is accomplished by "feeling" the arm slots with respect to the ventilator. These side arm problems are completely absent from the instant invention, where the control and locking means are clearly visible and simply operated.

To avoid such difficulties, the present invention provides control of the ventilator at both sides, where the control locking handles are grasped by the person who is installing, opening or closing the ventilator. The handles further serve as locking levers, and because they are positioned at each side of the ventilator, the closure is positive and distortion of the ventilator and/or the frame is avoided.

It is therefore an object of the invention to provide a basement window construction in which the window ventilator is arranged to tilt and open from the top, control and handles means being provided at each side thereof. Another object is to provide control and handle means that function also as locking levers. Still another object is to provide a ventilator that is independent of the window frame when the control locking means are disengaged therefrom. A further object is to produce a window that is less costly, more positive in operation, more efficient and effective, and easier to handle.

These and other objects of the invention will become more apparent from the description given below. The

2

description together with the appended drawings is a disclosure of one form which the invention may take, and is not intended to be a limitation of the forms and variations which persons skilled in the art may make. For 5 a visual understanding of the invention, reference is made to the accompanying drawings, in which—

Fig. 1 is a reduced front elevational view of the basement window embodying the inventive construction.

Fig. 2 is a vertical sectional view on the line 2—2 of 10 Fig. 1, parts being broken away.

Fig. 3 is a horizontal fragmentary sectional view of the ventilator control means substantially on the line 3—3 of Fig. 1.

Fig. 4 is a vertical fragmentary sectional view of the 15 ventilator tilted open in the window frame.

Fig. 5 is a horizontal sectional view taken on the line 5—5 of Fig. 1, parts being broken away.

As shown in Fig. 1, the basement window 10 comprises an outer frame 12, a ventilator 14, and control 20 handles 16 arranged at each side of the ventilator.

Frame 12 comprises a top bar 18, a bottom bar 20, and side bars 22, all of Z-section shape. Tilting stop pins 24 are riveted into the side bars 22 near the bottom thereof. Control handle locking pins 26 are riveted into 25 the side bars 22 substantially above the horizontal center line of the window.

Ventilator 14 consists of a top bar 28 and side bars 30, all of Z-section shape, and a bottom bar 32 of T-section shape. Bottom bar 32 is provided with a vertical 30 section 34 and a horizontal T-stem 36. Tilting pins 38 are riveted into bottom bar T-stem 36 to provide a pivoting means in tilting the window open, and as a pivoting means in locking the window along the frame bottom bar 20. A small section of T-bar vertical section 34 is 35 coped out at its ends to allow for adequate tilting of the ventilator before it is stopped by pins 24. These latter pins are located above the top edge of frame bottom bar 20 a distance sufficient to permit the ventilator T-bar 32 to slide out or through in order to remove the ventilator 14 from the frame 12. Insertion of the ventilator 40 is achieved by passing the T-bar 32 back into the frame between the tilting pins 24 and the frame bar 20.

Control handles 16 are arranged to swing in a vertical slot 40 cut in ventilator side bars 30, and pivot on pins 45 42 fixed in side bars 30. Control handles 16 have a broad flat handle portion 44, a web plate 46, normal to portion 44, through which pivot pin 42 passes, and a cam catch 48 arranged in parallel with but offset from handle portion 44 by the connecting web plate 46.

Control handles 16 are located on pins 42 substantially 50 above the horizontal center line or center of gravity of the ventilator 14 in order that when they are grasped, the ventilator will depend in a vertical fashion, thus giving greater control in handling the ventilator in or out of the frame, in tilting the ventilator open, or in closing it tightly in the frame.

Glass lights or panes 50 are sealed in the ventilator framing bars by means of putty 52, about a center T-section divider 54, in accordance with current window 60 practice.

Because of the side control, locking and camming action of the control handles 16, the perimetric contact of the ventilator and the frame is positive and complete. In addition, the camming action of the control handles 65 16 against locking pins 26 causes the ventilator T-bar 32 to bear firmly down against the frame bottom bar or sill 20, so as to make it substantially weathertight.

Another feature of the construction is that double contact is achieved between the top and side bars of both 70 ventilator and frame, thus making for an excellent weatherproof seal in the window. In Fig. 5, it will be

noted the side bar Z-sections bear against each other at two lines, front and rear, so that a positive double weathering contact is achieved.

In operation, the basement window here described functions by a very simple method. The window frame 12 is fixedly mounted in a window opening, arranged in a cement block, brick or poured concrete wall. The frame should be sealed in place to prevent moisture and air leaks about the frame bars. The ventilator 14 is then put into the frame by passing the bottom bar pins 38 over and down inside past the frame bottom bar 20, at the same time easing ventilator bottom T-bar 32 past tilting stop pins 24 on the frame side bars 22.

To lock the ventilator 14 in place, control handles 16 are pivoted and lifted upwardly so that the cam catches 48 pass under locking pins 26. Handle portions 44 are then pivoted downward to lie flush along ventilator side bars 30, swinging cam catches 48 behind and into firm camming engagement with locking pins 26.

To tilt ventilator 14 open, the control handle portions 44 are pivoted upward, releasing cam catches 48 from pins 26 and the ventilator is tilted outwardly at the top, swinging downward on tilting pins 38 until stop pins 24 engage bottom T-bar 32 and bring the ventilator to rest.

It will be seen from the above that all action and operation of the ventilator 14 takes place after the control handles 16 are grasped by the person operating the window. Such balanced control insures smooth functioning of the window in its installation, opening, closing or removal operations. More efficient closing is obtained because the window is cam latched above the center line, and there is practically no danger of leaving the window open when the control handles are pushed downward into locking position.

Because the control handle portions 44 are arranged and lie flat upon the ventilator side bars 30, damage to the handles is substantially eliminated. Also packaging for shipment, and stacking of the units in storage or shipment is considerably improved. These aspects of the invention bring about a substantial reduction in costs.

It will be obvious, of course, that the construction here disclosed is also applicable to residential, industrial and commercial windows.

Having described my invention in its simplest terms, it is to be understood that the details of the foregoing specification may be changed and varied in greater or lesser degree without departing from the essence of my invention.

I claim:

1. The combination of a metal window frame having jambs and outwardly extending flanges along at least the inner edges of said jambs, a metal window sash mountable upright within said frame, said sash having stiles at either side thereof, and a pair of handles, means pivotally mounting said handles on the stiles of said sash at

either side thereof, said handles having a grip portion adapted to be grasped by the hand and being arranged to be swung away from the sash in a vertical path normal to the plane of said sash into an open position and to be swung toward the sash to a locking position inwardly of the plane of said flanges of the jambs of said frame, said handles including a web portion having a sash-locking cam thereon disposed between the stiles of said sash and the jambs of said frame, said frame having members engageable by said cams for locking the sash in closed position, said sash and frame including cooperating elements for permitting the lower end of said sash to pivot relative to said frame and to permit removal of the sash from said frame upon upward movement of the sash relative to said frame, whereby said sash may be removed from said frame by grasping and swinging said handles into said open position and lifting said sash from said frame.

2. The combination defined in claim 1, in which the sash stiles have an inner edge portion and the handles have a shoulder that engages said inner edge portions of said sash stiles at a point adjacent the handle pivot means to limit movement of said handles into open position.

3. The combination of a removable window sash having stile members and top and bottom rail members, a window frame, and a pair of handles, said sash having coplanar flange elements on the inner side of each of the top and stile members adapted to engage said frame, said handles having grip portions and web portions connected thereto, said stile flange elements each having a slot, the web portion of said handles passing through the respective slots in said stile flange elements, means pivotally mounting said web portions on said sash at either stile flange element thereof in horizontal alignment above the center line of said sash, locking pins mounted on said frame, and sash locking cams on said web portions adapted to latch on said locking pins, said grip portions being arranged to pivot into a position flush with said sash when in its closed position and to swing outwardly from said sash in a vertical path normal to said sash into an opening position, whereby said sash may be lifted by grasping said handles and completely removed from said frame, said sash at such time pivotally hanging from said handle pivot means and assuming a substantially vertical position by gravity.
